UNITED STATES PATENT OFFICE

2,613,855

GREASE DISPENSER

Arthur Pansegrouw, Marshalltown, Iowa

Application March 22, 1949, Serial No. 82,716

3 Claims. (Cl. 222—340)

1

The present invention relates to new and useful improvements in grease dispensers and more particularly to a novel pressure means for forcing grease to a grease fitting.

An important object of the invention is to provide a portable dispensing apparatus including a grease chamber having a piston working therein to discharge the grease, and providing a jack under the piston as a removable unit to place the grease in the chamber under a desired pressure.

A further object is to provide spring means between the piston and jack placed under tension by the jack to hold the grease under pressure while being dispensed and without necessitating constant operation of the jack.

A still further object is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view;

Figure 2 is a vertical sectional view;

Figure 3 is a transverse sectional view taken on a line 3—3 of Figure 2, and

Figure 4 is an enlarged fragmentary sectional view taken on a line 4—4 of Figure 2.

Referring now to the drawing in detail, wherein for the purpose of illustration I have disclosed a preferred embodiment of my invention, the number 5 designates a cylindrically shaped tank which is positioned upright and closed at its bottom. The top of the tank is closed by a removable cover 6 secured in position by a bayonet slot connection 7 tightened by a partial turning movement of the cover in the usual manner. A gasket 8 is placed between cover 6 and the top of the tank.

A piston 9 provided with piston rings 10 has a working fit in tank 5 to form a grease chamber 11 in the upper portion of the tank which is filled with grease by removing cover 6.

The cover is provided with handles 12 to facilitate removing and replacing of the cover as well as for carrying the tank, and the cover is also provided with a dispensing hose 13; a pressure gauge 14; and a pressure relief valve 15.

A plurality of rods 16 are threaded in the un-

2

derside of piston 9 and extend downwardly therefrom and on which a bottom plate 17 is slidably. The plate is retained on the rods by nuts 18 threaded on the rods under the plate.

A coil spring 19 is positioned between piston 9 and plate 17 and compressed by an upward movement of the plate to subject grease in chamber 11 to pressure due to compression of the spring.

A conventional type of manually operated jack 20 is positioned under plate 17 and is operated by a handle 21 projecting outwardly at one side of tank 5 through an opening 22 therein. An annular flange 23 is secured to the inner wall 15 of the tank 5 above the opening 22, to limit downward movement of the plate 17, thereby permitting the jack 20 to be inserted and removed from the tank.

In the operation of the device, the chamber 20 11 is filled with grease, cover 6 secured tightly on top of tank 5 to close the chamber, and jack 20 operated to force plate 17 and piston 9 upwardly to compress the grease in the chamber. The upward movement of plate 17 also places 25 spring 19 under compression whereupon grease may then be dispensed through hose 13 to a grease fitting in the usual manner.

During the dispensing operation, the spring 19 will continue to force the piston upwardly and retain the grease under pressure for a prolonged period after the operation of jack 20 has ceased.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described my invention, what is claimed as new is:

1. A grease dispenser comprising a cylindrical tank having a cover on one end thereof, a grease dispensing conduit attached to said cover and 50 communicating with said tank, a piston slidably received in said tank and forming a grease chamber therein between said piston and said cover, a plate slidably received in said tank below said piston, a coil spring disposed between said piston and said plate, a plurality of circumferentially

spaced guiding rods attached to the under surface of said piston equidistant from the center thereof, said rods extending longitudinally of said tank and embracing the convolutions of said coil spring internally thereof to guide said spring between said wall and said rods during the expansion and contraction of said spring, said plate having bores therein slidably receiving said rods, locking means on the lower end of said rods underlying said plate to limit displacement of said plate relative to said piston, elevating means underlying said plate selectively urging said plate upwardly to compress said spring, sliding of said plate toward said piston being unobstructed except by said coil spring, said spring urging said piston upwardly to force grease from said chamber.

2. A grease dispenser comprising a cylindrical tank having a cover on one end thereof, a grease dispensing conduit attached to said cover and communicating with said tank, a piston slidably received in said tank and forming a grease chamber therein between said piston and said cover, a plate slidably received in said tank below said piston, a coil spring disposed between said piston and said plate, a plurality of circumferentially spaced guiding rods attached to the under surface of said piston equidistant from the center thereof, said rods extending longitudinally of said tank and embracing the inner side of said coil spring to guide said spring between said wall and said rods during the expansion and contraction of said spring, said plate having bores therein slidably receiving said rods, locking means on the lower ends of said rods underlying said plate to limit displacement of said plate relative to said piston, elevating means underlying said plate selectively urging said plate upwardly to compress said spring, sliding of said plate toward said piston being unobstructed except by said coil spring, said spring urging said piston upwardly to force grease from said chamber, said elevating means including a jack, said casing having a bottom wall thereon and a lateral aperture in the lower portion of the casing above said bottom wall, said jack being removably placed bodily through said aperture into said tank to rest on said bottom wall and in jacking engagement with said plate, said jack being actuatable through said aperture.

3. A grease dispenser comprising a cylindrical tank having a cover on one end thereof, a grease dispensing conduit attached to said cover and communicating with said tank, a piston slidably received in said tank and forming a grease chamber therein between said piston and said cover, a plate slidably received in said tank below said piston, a coil spring disposed between said piston and said plate, a plurality of circumferentially spaced guiding rods attached to the under surface of said piston equidistant from the center thereof, said rods extending longitudinally of said tank and embracing the inner side of said coil spring to guide said spring between said wall and said rods during the expansion and contraction of said spring, said plate having bores therein slidably receiving said rods, locking means on the lower ends of said rods underlying said plate to limit displacement of said plate relative to said piston, elevating means underlying said plate selectively urging said plate upwardly to compress said spring, sliding of said plate toward said piston being unobstructed except by said coil spring, said spring urging said piston upwardly to force grease from said chamber, said elevating means including a jack, said casing having a bottom wall thereon and an aperture in the lower portion thereof, said jack being removably placed through said aperture into said tank between said bottom wall and said plate, said jack being actuatable through said aperture, and a flange disposed in said tank above said aperture and supporting said plate in an elevated position in the tank to form a chamber in the lower portion of the tank for the jack and accessible through the aperture.

ARTHUR PANSEGRAU.
